UNITED STATES PATENT OFFICE

LOUIS E. ENDSLEY, OF PITTSBURGH, PENNSYLVANIA, ASSIGNOR TO FORT PITT MINE EQUIPMENT COMPANY, OF PITTSBURGH, PENNSYLVANIA, A CORPORATION OF PENNSYLVANIA

CAR RETARDER

Application filed October 8, 1928. Serial No. 310,995.

My invention relates to track brakes or car retarders, such as those employed for checking or retarding the movement of railway cars, mine cars and the like, through friction imposed against the sides of car wheels, thus avoiding the necessity of employing the hand brakes of the cars for retarding movement thereof.

One of the objects of my invention is to provide a car retarding device of much simpler form than those of various types heretofore employed.

Another object of my invention is to provide a car retarder or track brake of such form that there is a minimum loss through friction of the working parts in transmitting the power therethrough to operate the braking devices.

Another object of my invention is to provide a device of the character referred to, wherein there is little danger of the parts becoming disarranged or rendered ineffective through foreign matter or obstructions coming into contact therewith.

A further object of my invention is to provide a device wherein the braking forces which are applied to car wheels at a plurality of points are effectively equalized.

Still another object of my invention is to provide a car retarding device that occupies a small amount of space compared to various structures heretofore employed.

One form which my invention may take is shown in the accompanying drawing, wherein Figure 1 is a plan view of the structure, with a portion of the operating mechanism broken away; Fig. 2 is a side elevational view of the structure, and Fig. 3 is a sectional view taken on the line III-III of Fig. 1.

The apparatus is shown as employed in connection with track rails 4 and 5 along which cars 6 are to be moved. Suitably mounted on the cross ties or in some other convenient manner, I provide Z bars 7 which serve to support gripping bars or shoes 8 in position to be moved against the sides of the car wheels, to check the movement of the car. These shoes are shown as having

wear plates secured thereto for frictional contact with the car wheels.

Power for actuating the gripping bars may be derived either from a hand lever 9 or other suitable source. By reason of the arrangement hereinafter described, manual power applied through the lever 9 will usually be sufficient to check the movement of lighter cars, such as mine cars.

The hand lever 9 is secured to a shaft 10 that is mounted in suitable bearings and which carries at its inner end a crank 11. The crank 11 is connected to one end of a link 12 whose other end has connection with a crank 13 that is secured to a rock shaft 14. The shaft 14 carries a crank-like lifting arm 15 which extends through an opening in an equalizing lever 16. The outer end of the arm 15 is curved, so that the lever 16 can slide thereon slightly, thus permitting the lever to move in approximately a true vertical path and avoiding binding thereof and of the links to which it is connected as hereinafter described.

The lever 16 supports a pair of links 17 each having its lower end connected to a lever 18 of bell crank form. The upper extremity of this lever 18 has pivotal connection with the inner gripping bar 8, while its other outer extremity is pivotally connected to a pull rod or bar 19 whose outer end is bent upwardly and has slidabile engagement with a rod 20 that is connected to an outer shoe 8, a spring 21 being interposed between said shoe and the adjacent end of the pull rod.

A bracket 23 of yoke-like form is secured to each of the outer Z bars, and each serves as a guide for its associated pull rod 19 during sliding movement thereof, sufficient clearance being provided in each of the brackets 23 to permit slight vertical movements of the pull rod. A bracket 24 is provided for guiding the lower outer end of each of the levers 18.

At the opposite end of the structure, I provide a similar arrangement of mechanism for operating the gripping bars or shoes, such mechanism being substantially a duplicate of that just described, so far as the

lifting crank 15, lever 16, levers 18, pull rods 19, and the associated parts are concerned. A link or pull rod 26 is connected to the crank 13 at one end and at its other end has connection with a crank 13^a that is mounted on a rock shaft 14^a which corresponds to the rock shaft 14.

The gripping bars 8 are bent laterally at each end, as shown more clearly in Fig. 1, 10 to provide a flared opening into which the car wheels may roll without danger of becoming caught on the ends of such bars. Stop plates 27 are riveted to the ends of bars 8, and these plates engage the ends of the Z 15 bars 7 to prevent shifting of the bars 8 longitudinally.

When it is desired to check the movement of a car which is advancing along the track rails 4 and 5, the hand lever 9 is moved to 20 operative position such distance as may be required in order to bring the gripping bars 6 into engagement with the sides of the car rails with the required degree of force, depending upon the weight of the car and the 25 extent to which the speed thereof is to be reduced. Such movement of the hand lever 9 results in upward movement of the outer ends of the lifting cranks 15, so that the levers 16 are elevated and the levers 18 rocked 30 through lifting of their inner ends. This rocking movement of the levers 18 results in the upper ends thereof being forced toward the car wheels and their lower outer ends drawn inwardly to impart inward movement to the pull rods 19. The gripping bars 8 are thus forced against the car wheels and retard movement thereof.

Since the levers 16 are free to rock during this movement and they are connected to 40 links 18 which are pivoted at each end, and as the members 18 and 19 are pivotally connected, there is equalization of forces applied against the sides not only of each car wheel, but also with respect to each pair of 45 car wheels. The springs 21 provide the necessary yielding effect to prevent such binding of the car wheels between the shoes 8 as might result from unevenness in the faces of the wheels.

50 By the elimination of a number of fixed pivotal points heretofore deemed necessary, I secure better equalization of braking forces and reduce frictional losses which would otherwise occur in the transmission 55 of power to the shoes.

Again, it will be seen that although the pull rods 19 extend beneath the rails, they do so only in horizontal directions, and have substantially only horizontal movement, so 60 that but a small amount of clearance is required beneath the rails, thus making for quick and convenient installation and rendering the moving parts less subject to obstruction against movements thereof.

65 I claim as my invention:—

1. Car retarding apparatus comprising a pair of shoes, a lever having pivotal engagement with one of said shoes, a pull rod having engagement with the other shoe and pivotally connected to the said lever, and means 70 for rocking the lever about the first-named pivotal point.

2. Car retarding apparatus comprising a pair of shoes, a lever having pivotal engagement with one of said shoes, a pull rod disposed in a horizontal plane and having an upturned end in engagement with the other shoe and pivotally connected to the said lever, and means for rocking the lever about the first-named pivotal point. 75

3. Car retarding apparatus comprising two pairs of shoes, a pair of levers each having pivotal engagement with one of said shoes, a pair of pull rods each having engagement with the other shoe of each pair 80 and each pivotally connected to one of said levers, an equalizing lever connected at each end to one of said levers, and means for actuating said equalizing lever to effect movement of the first-named levers. 85

4. Car retarding apparatus comprising two shoes, a pair of horizontally disposed rods each having a transversely bent end for engaging one of said shoes, an equalizing lever connected at each end to one of said rods, and means for actuating said equalizing lever for effecting longitudinal movement of the rods. 95

5. Car retarding apparatus comprising two shoes, a pair of pull rods each having engagement with one of said shoes and mounted for movement bodily, an equalizing link, a pivotal connection between each end of said link and one of said rods, and means for actuating said link to effect movement of 100 the rods. 105

6. Car retarding apparatus comprising two shoes, two pull rods each extending in a horizontal direction but having one end turned laterally for engagement with one of said shoes, an equalizing lever, means for pivotally supporting the lever intermediate its ends and movable in a direction transversely of the pivotal connection, and link connections between each end of said lever 110 and one of the rods arranged to cause movement of the rods in directions longitudinally thereof upon lateral movement of the lever.

7. Car retarding apparatus comprising two shoes, two pull rods each extending in a horizontal direction but having one end turned laterally for engagement with one of said shoes, an equalizing lever, link connections between each end of said lever and one of the rods arranged to cause movement of the rods in directions longitudinally thereof upon lateral movement of the lever, a crank having engagement with said lever 120 to shift the same in a lateral direction, a rock 125

shaft for actuating said crank, and means for oscillating said rock shaft.

8. Car retarding apparatus comprising two pairs of shoes, two levers each having pivotal engagement with one shoe of each pair, two pull rods each having engagement with the other shoe of said pair and pivotally connected to one of said levers, a lifting link connected to each of the levers, an equalizing lever connected at its ends to the said lifting links, and means for moving said lever in a direction transversely thereof.

9. Car retarding apparatus comprising shoes, links connected to said shoes and disposed in a common plane, an equalizing lever having each of its ends connected to one of said links, and a lifting arm mounted for rocking movement in a direction transversely of the axis of the lever but connected to said lever for operating the same in a direction parallel to the plane of the links and the lever, the said lever and arm having relative movement in a direction axially of the arm.

In testimony whereof I, the said LOUIS E. ENDSLEY have hereunto set my hand.

LOUIS E. ENDSLEY.
